(57) **CLAIM**

The ornamental design for a camisole and brassiere combination, as shown and described.

DESCRIPTION

FIG. 1 is an isometric front perspective view of a camisole and brassiere combination in accordance with an embodiment of my new design;

FIG. 2 is a front elevational view thereof;

FIG. 3 is a rear elevational view thereof; and,

FIG. 4 is a top plan view thereof.

The broken lines in the Figures are for the purpose of illustrating exemplary environmental structure and form no part of the claimed design.
